(57) **CLAIM**

The ornamental design for a lipstick removal device, as shown and described.

DESCRIPTION

FIG. 1 is a top view of a lipstick removal device, showing the new design;

FIG. 2 is a bottom view thereof;

FIG. 3 is a left side view thereof;

FIG. 4 is a front view thereof;

FIG. 5 is a rear view thereof;

FIG. 6 is a side perspective view thereof;

FIG. 7 is a top perspective view thereof; and,

FIG. 8 is a bottom perspective view thereof.

The uniformly dashed lines shown in the drawings illustrate portions of the lipstick removal device which form no part of the claimed design.
